CLAIM

The ornamental design for an automatic coffee machine for commercial purposes, as shown and described.

DESCRIPTION

3. Automatic coffee machine for commercial purposes

4. Automatic coffee machine for commercial purposes

3.1 : Perspective

3.2 : Front

3.3 : Back

3.4 : Left

3.5 : Right

3.6 : Top

4.1 : Perspective

4.2 : Front

4.3 : Back

4.4 : Left

4.5 : Right

4.6 : Top

Figs. 3.1, 4.1 are top, front and right side perspective views showing our new design; Figs. 3.2, 4.2 are front elevational views thereof; Figs. 3.3, 4.3 are rear elevational views thereof; Figs. 3.4, 4.4 are right side elevational views thereof; Figs. 3.5, 4.5 are left side elevational views thereof; and Figs. 3.6, 4.6 are top plan views thereof; the automatic coffee machine according to either of the above embodiments is a heavy article that cannot be viewed from the bottom; the bottom plate thereof is not part of the claimed design.
